ATTORNEY

UNITED STATES PATENT OFFICE

128,780

DESIGN FOR A COMBINATION TUMBLER AND TOOTHBRUSH HOLDER

Gustave A. Hallenscheid, Los Angeles, Calif.

Original application November 13, 1939, Serial No.
88,222. Divided and this application December
23, 1940, Serial No. 97,552

Term of patent 14 years

To all whom it may concern:

Be it known that I, Gustave A. Hallenscheid, a citizen of the United States, residing at Los Angeles, county of Los Angeles, State of California, have invented a new, original, and ornamental Design for a Combination Tumbler and Toothbrush Holder, of which the following is a specification and which invention is a division of my application Serial No. D-88,222, filed November 13, 1939, reference being had to the accompanying drawing, forming a part thereof.

I claim:

The ornamental design for a combination tumbler and toothbrush holder, as shown.

GUSTAVE A. HALLENSCHEID.
